HASSOCK

Marvin Herman, East Meadow, N.Y., assignor, by mesne assignments, to Cone Mills Corporation, Greensboro, N.C., a corporation of North Carolina

Filed Mar. 15, 1967, Ser. No. 6,223

Term of patent 14 years

(Cl. D33—8)

FIG. 1

FIG. 2

FIG. 4

FIG. 1 is a top plan view of a hassock embodying my design;

FIG. 2 is a side elevational view of FIG. 1;

FIG. 3 is a front elevational view of FIGS. 1 and 2; and

FIG. 4 is a rear elevational view of FIGS. 1 and 2.

The dominant features of my design reside in those portions shown in full lines on the drawing. The side not shown is a mirror image of the side shown.

I claim:

The ornamental design for a hassock, as shown and described.
